SEMICLOSED CIRCUIT TYPE GAS TURBINE PLANT HAVING EXTRACTION CONTROLLED BY CIRCUIT TURBINE GOVERNOR

Rene Strub, South Charleston, W. Va.

Continuation of application Serial No. 557,616, October 7, 1944. This application January 10, 1951, Serial No. 205,318. In Switzerland December 23, 1943

11 Claims. (Cl. 60—39.18)

1

This application is a continuation-in-part of my copending application, Serial No. 557,615, filed October 7, 1944, and a continuation of my copending application Serial No. 557,616, filed October 7, 1944, both now abandoned.

The invention relates to a gas-turbine plant with the working medium performing a circuit from which a partial quantity is continuously extracted while in its place a make-up quantity is supplied, at least one turbine being operated by the quantity of medium flowing in the circuit and at least one other turbine by the working medium extracted from the circuit. It consists in that the output of the extraction turbine is adjusted to different values by alteration of the speed of the circuit turbine.

The governor of the circuit turbine can adjust the extraction of working medium from the circuit and in particular the supply of working medium to the extraction turbine. The speed governing arrangement has in given cases a device for adjusting the normal speed of the circuit turbine. At least one compressor of the plant can be provided with a bypass pipe the flow regulating member of which is adjusted by the governor of the circuit turbine. The device for adjusting the normal speed of the circuit turbine may further adjust the fuel supply to the gas heater.

The invention is explained in more detail below with the aid of the drawings, in which:

Fig. 1 illustrates schematically an embodiment of gas-turbine plant in accordance with the principles of this invention, and

Fig. 2 shows a hydraulic regulating device which can be employed for the gas-turbine plant shown in Fig. 1. Identical elements appearing in the two figures are denoted by the same numerals.

The gas-turbine plant shown in Fig. 1 works with a circuit of a gaseous working medium, for instance air, from which a partial quantity is continuously extracted and to which in return a make-up quantity is continuously supplied. The working medium compressed by the low-pressure compressor 1 passes through the intermediate cooler 2 into the high-pressure compressor 3. After being brought to the highest pressure, it flows through the pipe 4 into the heat-exchanger 5, in which it is preheated while flowing through the tubes 6. Through the pipe 7 the working medium flows further until it is divided up into two parts at the point 8.

The major part passes through the pipe 9 into the gas heater 10 and is brought up to its highest temperature while flowing over the heat-ex-

changer tubes 11 and is then supplied through the pipe 12 to the turbine 13. The working medium is expanded in the turbine, passes through the pipe 14 into the heat-exchanger 5 and here, while flowing over the heat-exchanger tubes 6, gives up part of its residual heat to the working medium flowing through the tubes. The working medium passes further through the pipe 15 into the cooler 16, in which a further part of its residual heat is given up to a cooling-medium. Finally the working medium is again supplied through the pipe 17 to the low-pressure compressor 1, in which the circuit begins anew.

From the circuit of the working medium described a partial quantity is continually extracted at the point 8 and is supplied as combustion air through the pipe 18 to support the combustion of fuel supplied by the burner 19 of the gas heater 10. This combustion air, mixed with products of the combustion and in a greatly heated condition, flows through the heat-exchanger tubes 11, in which a portion of its heat is given up to the working medium of the circuit flowing over the tubes. Afterwards the combustion gases pass through the pipe 20 into the turbine 21.

In order to replace the quantity of working medium extracted from the circuit at the point 8, air from atmosphere is continuously supplied to the circuit by the compressor 22. This make-up quantity is introduced into the heat-exchanger 5 through the pipe 23 at a point 24 at which the working medium flowing over the heat-exchanger tubes 6 is approximately at the same temperature and the same pressure as the make-up quantity.

The turbine 13 operated by the quantity of working medium flowing in the circuit drives the compressors 1, 3 and 22, while the turbine 21 operated by the partial quantity extracted from the circuit works as a useful output turbine, for instance driving a ship's propeller 26 through a reduction gear 25. The turbine 13 and the compressors 1, 3 and 22 are further coupled to 3-phase constant speed electric machine 27 which serves as a starting motor and as an auxiliary dynamo or motor for equalizing surplus or lacking power.

The output of the extraction turbine 21 is adjusted to various values by the changing of the speed of the circuit turbine 13. In order to keep the speed of the circuit turbine 13 and of the compressors 1, 3 and 22 to a normal value set, the supply of working medium to the extraction turbine 21 is adjusted by the governor 28 of the cir-

cuit turbine. The governor 28 controls a flow regulating member 32 through the medium of an impulse transmitter 29, the impulse pipe 30 and the servomotor 31. The flow regulating member is arranged in a bypass pipe 33 which supplies working medium from the pipe 20, while bypassing the first stage of the turbine 21, to the following stages. The impulse transmitter 29 is designed as an isodrome device. The term "isodrome" is a common one outside the United States and is here used in the sense of "tending to return to the same position." The use of the term in this sense is fully explained and a number of isodrome devices are illustrated in a work of German origin on governors, "Die Regelung der Kraftmaschine," by Fabritz, published under the authority of the Alien Property Custodian by J. W. Edwards at Ann Arbor, Michigan, 1944, and also in "Regelung der Kraftmaschine," by Max Tolle, 3rd Edition, pp. 818, 872-874. Further see U. S. Patent 1,748,506. After each regulating process it reestablishes the normal speed in the circuit turbine 13, however great the load on the turbine may be. A lasting irregularity cannot present itself.

The cross-section of flow of the regulating member 32 is reduced as soon as the speed of the turbine 13 falls below the normal value, but it is on the other hand increased as soon as the speed of the turbine 13 rises above the normal value. A diminution of the cross-section of flow of the regulating member 32 has the effect that a smaller quantity of working medium is extracted from the circuit. In consequence, the quantity of working medium which flows through the combustion chamber of the gas heater 10 decreases, so that the temperature in the combustion chamber of the gas heater 10 becomes higher. Through the pipe 9 a larger quantity of working medium is supplied to the gas heater and then through the pipe 12 to the turbine 13.

The turbine 13 thus receives an increased quantity of working medium with greater heat content, so that the initial drop of speed of the circuit turbine below the normal, which started the regulating process, is again made up. Contrarily, an increase in the cross-section of flow of the regulating member 32 causes the extraction from the circuit to become greater. A smaller quantity of working medium with lower heat content is then supplied to the turbine 13, so that the speed of the circuit turbine, which originally rose, is again returned to the required normal value.

The impulse transmitter 29 has a device 34 with the aid of which the normal value which is maintained by the governor 28 can be adjusted by hand to correspond to the desired output of the whole plant. If a smaller normal value is adjusted for the speed of the circuit turbine, a smaller useful output is obtained at the turbine 21; with a higher normal value, a greater useful output is obtained.

The temporary influencing of the supply of working medium to the extraction turbine 21 during the regulating process has no disadvantageous results for the service of the plant, as this secondary influence ceases again when the new level of steady running has been set. In particular when the plant is employed for marine propulsion, the brief and slight change of speed resulting herefrom is of no significance.

In the discharge pipe 35, which leads from the supply pipe 20 of the extraction turbine 21 and directly into the discharge pipe 36, bypassing the turbine, a flow regulating member 37 is built.

The servomotor 38 is influenced by the governor 40 of the extraction turbine 21 by way of the impulse pipe 39. In the supply pipe 20 a further closing member 41 is placed, and this is also controlled by the governor 40 with the aid of the servomotor 42 by way of the impulse pipe 43. The servomotor 38 of the regulating member in the discharge pipe 35 may further be influenced by the governor 28 of the circuit turbine 13 by way of the impulse pipes 44 and 30 and the impulse transmitter 29.

The flow regulating member 37 in the discharge pipe 35 and the closing member 41 act in common as a rapid-closing device, in order immediately to interrupt the supply of working medium to the extraction turbine 21 when the limit of the admissible speed range is exceeded. A sudden interruption of the output given up is necessary if the speed of the turbine 21 should rise inadmissibly high, for instance if the propeller should emerge from the water in high seas or if a variable pitch propeller should not function, and on the other hand if for instance the power given up must be rapidly interrupted on account of danger.

If the limit of admissible speed is reached by the extraction turbine 21, the governor 40 influences the servomotors 38 and 42 simultaneously in such a way that the flow regulating member 37 is opened and the closing member 41 is closed. The combustion gases of the gas heater 10 then no longer flow to the turbine 21, but through the discharge pipe 35 direct into the discharge pipe 36. Through the influencing of the servomotor 38 by means of the governor 28 the cross-section freed by the flow regulating member 37 in case of rapid closing is set to correspond to the speed of the circuit turbine and the load on the whole plant.

If rapid closing takes place at low load, at which only a small quantity of working medium is supplied to the turbine 21, the cross-section of flow of the member 37 in the pipe 35 is smaller than at higher loads with a correspondingly greater quantity of working medium. The cross-section of flow set by the member 37 in case of rapid closing is so measured by the governor 28 that after rapid closing just as much working medium is passed through the discharge pipe 35 as immediately before rapid closing through the extraction turbine 21. In this way the end is attained that rapid closing can have no direct reactions on the circuit portions of the plant.

The flow regulating members 47 and 51 and the throttling member 55 come into action in succession when the load is greatly reduced and during no-load running, in order to prevent the compressors from pumping. With the flow regulating members single stages or a whole compressor can be bypassed, so that the reduced quantity of working medium only flows through part of the compressor stages. In this way pumping is prevented.

The compressor 22 has a bypass pipe 45 which connects the suction pipe 46 to an intermediate stage. In this bypass pipe is arranged the flow regulating member 47 which is controlled by a servomotor 48. The servomotor 48 is in communication through the impulse pipe 49 with the impulse transmitter 29.

Between the coolers 16 and 2 a communication exists through the pipe 50, in which is built the flow regulating member 51. The flow regulating member is influenced with the aid of a servomotor 53, which is connected through the im-

pulse pipes 54 and 49 to the impulse transmitting device 29. With the aid of this bypass pipe the low-pressure compressor 1 can be cut out, so that the working medium from the pipe 15 passes direct through the cooler 16 and the intermediate cooler 2 into the high-pressure compressor 3.

In the suction pipe 46 of the compressor 22 is built the throttling member 55, which is influenced by means of the servomotor 56 from the impulse transmitter 29 through the pipes 49 and 51.

First the regulating member 47 of the compressor 22 is opened by means of the governor 28 through the impulse transmitter 29, and then the regulating member 51 of the low-pressure compressor 1 is opened. Finally a further decrease of the output is obtained by reducing the cross-sectional area of pipe 46 left free by throttling member 55 for the flow of working medium. The bypass member 47 allows part of the air delivered by the supercharging compressor 22 to flow back into the suction pipe, so that a lower pressure of the working medium in the circuit, corresponding to the lower load, is set. When the valve 51 is opened, the low-pressure compressor 1 is bypassed. The high-pressure compressor 3 will then in consequence of the lower pressure at which it receives its input, deliver the working medium flowing in the circuit at a lower pressure. When the suction pipe of the supercharging compressor 22 is throttled by the regulating member 55, the pressure of the working medium is finally reduced to such an extent that the plant can run without load at the normal speed.

The fuel supply to the gas heater must be altered to correspond to the output set by the speed. It must be possible for the process of adaptation to be accelerated by hand during the change of output. For this purpose there is in the fuel pipe 58 of the burner a regulating member 59 whose servomotor 60 can be influenced through the impulse pipes 30 and 64 by the hand setting device 34 of the impulse transmitter 29. Further, an influence is exerted by the temperature of the working medium in the pipe 12 by means of the temperature impulse transmitter 63 acting through the pipe 62, and finally an influence is exerted by the pressure in the combustion chamber of the gas heater 10 acting through the impulse pipe 61.

The regulating device shown in Fig. 2 may be used for the gas-turbine plant shown in Fig. 1. The governor 28 is driven by the shaft 74 of the circuit turbine. It influences by way of an isodrome device the regulating member 32 in the bypass pipe 33 of the extraction turbine in such a way that the normal speed set for the circuit turbine with the aid of the hand setting device 34 is maintained. The isodrome device is equipped with a yielding return system and consists of the servomotor 31 with the control valve 15, the return drag device 76 and the spring 77.

The isodrome device can only come to rest when the lever 78 is in a position in which the spring 77 is without load and the control valve 15 is in its middle position and covers the control passages 79 and 80 of the servomotor 31. The lever 78 can only come into this situation at one position of the governor 28, namely that position which corresponds to the normal speed set by the lever 34.

If the speed of the circuit turbine rises above the normal speed set the governor collar 81 is lifted. The fulcrum 82 of the lever 78 at first

remains unmoved, but the valve 15 is drawn upwards. Pressure fluid can make its way from the pipe 83 through the control passage 80 into the cylinder space situated above the servomotor piston 84. The piston is pressed downwards, so that by means of the lever 85 and the yoke 86 the cross-section of flow of the regulating member 32 is enlarged. A larger quantity of working medium now flows to the extraction turbine and a smaller quantity to the circuit turbine. The initial speed deviation which started the regulating process is thus redressed.

A similar regulating process, but taking place in the opposite direction, sets in when the speed of the circuit turbine falls below the normal. Then the cross-section of flow of the regulating member 32 is diminished by the governor 28 with the aid of the isodrome device. Less working medium flows to the extraction turbine, and more to the circuit turbine, so that the speed again rises to the normal value.

In order to avoid overregulation and the oscillation that might then be caused, the servomotor piston 84 brings the control valve 15 back towards its middle position during the regulating process by means of the drag coupling 76 and the lever 78. Meanwhile the spring 77 is stressed. In this way a force comes into action on the casing of the drag coupling 76 which also acts through the fluid contents of the cylinder spaces upon the drag piston 87. In the cylinder space below the drag piston there arises, in the case of a rise in speed, a greater pressure than that in the cylinder space above the drag piston, so that the fluid contents below the piston pass through the throttle passage 88 of the piston into the upper cylinder space.

The displacement of the piston 87 in the cylinder of the drag device 76 continues until the spring 77 is without tension and the valve 15 remains in the middle position. The servomotor piston 84 is then no longer displaced and no further spring force is exerted on the drag coupling. This position of rest is only possible when the governor 28 is brought back exactly into the position corresponding to the normal speed set and thus the circuit turbine operating the governor has again reached the normal speed required.

By means of the lever 34 the required normal value for the speed of the circuit turbine and thus the required useful output of the whole plant can be set. If the lever is moved in the minus direction of the double-headed arrow 89, the spring 77 is placed under further tension. The lever 78 can then only come to rest in one position, in which the position of the governor collar 81 is correspondingly lower and the value of the normal speed is accordingly reduced. The useful output is then likewise diminished.

Contrarily, when the lever is moved in the plus-direction of the double-headed arrow 89, the normal speed is raised. The spring 77 is compressed, the position of rest of the governor collar 81 will thus lie higher and the normal speed of the circuit turbine to be maintained will be raised correspondingly. At the increased speed, an increased output is given off.

The regulating member 37 in the discharge pipe 35 branching off from the supply pipe 20 of the extraction turbine and the closing member 41 in the supply pipe 20 are influenced with the aid of the governor 40 operated by the shaft 90 of the extraction turbine if the speed of this

turbine rises above the upper limit of the admissible speed range.

At admissible speed of the extraction turbine the control valve 91 is in a position in which pressure fluid from the pipe 92 can flow into the pipe 93. This pressure fluid passes into the cylinder spaces above the pistons 94 and 95 of the servomotors 38 and 42, so that the regulating member 37 is closed and the closing member 41 is opened. The working medium flows through the pipe 20 without any hindrance into the extraction turbine.

If the speed of the extraction turbine reaches the upper limiting value of the admissible speed range, the collar 97 is lifted by means of the lever 96. The valve 91 arrives in an upper position in which the connection between the pipes 92 and 93 is interrupted, while on the other hand communication is established between the pipes 92 and 98. The high-pressure fluid now flows into the cylinder spaces below the servomotor pistons 94 and 95. The valve of the regulating member 37 is lifted until the servomotor piston 94 comes up against the piston 99 and the closing member 41 is brought into the completely closed position.

The piston 99 is set through the yoke 86 and the isodrome device by the governor 28 of the circuit turbine and thus serves as an adjustable stop in such a way that the quantity of working medium led off through the discharge pipe 35 is just as great as the quantity of working medium flowing through the pipe 20 to the extraction turbine immediately before interruption. By this means the end is attained that when rapid closing of the extraction turbine takes place there are no direct reactions on the working of the circuit.

Rapid closing can also be brought about when the lever 34 is displaced into its end position in the minus direction of the double-headed arrow 89. Then the valve 91 is lifted by means of the lever 78 and the push rod 78A, so that pressure medium out of the pipe 92 can flow through the pipe 98 to the servomotors 38 and 42. Finally the governor 28 of the circuit turbine can also, at too high speeds, bring the valve 91 into the rapid closing position by means of the lever 78. Such an action takes on special significance if trouble occurs in service.

Independently of the isodrome device the governor 28 controls the flow member 47 in the bypass pipe 45, the flow regulating member 51 in the bypass pipe 50 and the throttling member 55 in the suction pipe 46 in accordance with the speed of the circuit turbine, in order at low outputs to prevent any surging in the compressors. The lever 100 is turned about the fixed point 101 by the collar 81. When the speed of the circuit turbine rises, the throttling member 102 frees a larger cross-section of flow, and when the speed falls, a smaller cross-section of flow. Fluid is supplied to the servomotors 48, 53 and 56 by the gearwheel pump 103, the pressure of this fluid rising higher in proportion as the cross-section freed by the throttling member 102 is smaller. The springs which load the pistons of the servomotors 48, 53 and 56 are so chosen relatively to each other that first the servomotor 48, then, when the control pressure rises, the servomotor 53, and finally, at the highest control pressure, the servomotor 56 come into action.

At a certain speed of the circuit turbine the fluid pressure is so high that the piston of the servomotor 48 raises the valve of the regulating

member 47. As the speed falls, the cross-section of flow past the regulating member 47 becomes greater and greater. During the falling of the speed and the corresponding rise of the control pressure in the servomotors, the piston of the servomotor 53 also begins to lift the valve 51. When the speed is very low, the pressure is so high that the piston of the servomotor 56 presses the member 55 towards the closed position.

For accelerating the adaptation of the fuel quantity to a changed load, the fuel supply to the burner 19 can be set by hand and further automatically by the temperature of the heated working medium. The flow regulating member 59 arranged in the fuel pipe 58 has a valve 104 which can be set by means of the hand lever 34 and additionally by the temperature impulse transmitter 63 in the pipe 12 for the heated gas. The possibility of setting the quantity in this way is limited by means of the pressure impulse transmitter 105 in such a way that oscillations of the regulating system are prevented.

The hand lever 34 acts through the linkage 129 and the lever 130 on the lever 121, which adjusts the valve 104 of the regulating member 59 through the spring 122 and the rod 106. If the lever 34 is displaced in the plus-direction of the double headed arrow 89, the valve 104 is drawn downwards in the plus-direction of the double-headed arrow 116 and the fuel supply increased. A decrease in the temperature during the rise of output is then prevented.

A movement of the lever 34 in the minus direction causes correspondingly a decrease in the fuel supply. In this way a rise of the temperature during the decrease of output is prevented.

The exact setting of the temperature to the normal after a change in the output is performed automatically by the temperature impulse transmitter 63. The rod of the impulse transmitter 63 is sensitive to temperature and has a coefficient of thermal expansion which is considerably greater than that of the tube 12 surrounding it. The expansion due to heat is transmitted through the levers 117 and 118, the servomotor 119, the link 120, the lever 121 and the spring 122 to the rod 106 of the fuel regulating member 59. A rise of temperature in the pipe 12 causes the control valve 123 in the servomotor 119 to be lifted. As a result pressure fluid passes from the pipe 124 into the cylinder space situated above the servomotor piston 125, so that the piston is lowered. The cross-section of flow of the fuel regulating member 59 is diminished through the lever 126, the link 120, the lever 121, the spring 122 and the rod 106. The rise in temperature which initially caused the regulating process is neutralized by the decrease of the fuel quantity supplied.

The corresponding regulating process sets in when the temperature falls below the normal. The fuel supply is then increased, so that the temperature is again raised.

The servomotor 125 further influences the return drag device 127, by which the return lever 118 is displaced and the spring 128 is loaded. By the displacement of the lever 118 the control valve 123 is again returned towards its middle position when a regulating process begins to take effect, so that the further deviation of the servomotor piston 125 is damped or interrupted.

The whole regulating device comes to rest only in one definite position of the lever 118, namely that in which the spring 128 is without load and the valve 123 is in its middle position. This mid-

idle position corresponds to the normal temperature to be set by the thermostat 63.

For limiting deviations a pin 107 is attached to the rod 106 of the valve 104, and this engages with the cam surfaces of the opening 108 in the plate 109. This plate is displaced in the directions of the double-headed arrow 113 by means of the rod 110 and the lever 111 by the piston 112 of the pressure impulse transmitter 105. An increase in the pressure in the combustion chamber of the gas heater 10 gives rise to a displacement in the plus-direction of the double-headed arrow 113, a decrease in the pressure in the combustion chamber to a displacement in the minus direction. This displacement can be further influenced by hand by turning the lever 114 in the plus or minus direction of rotation of the double-headed arrow 115.

The cam surfaces of the opening 108 have such a form that at the various pressures prevailing in the combustion chamber of the gas heater 10, or at the various loads for the fuel regulating member 59, a range of regulation is set-up in which no oscillations of the regulating system can arise. In case of large fuel quantities the range of regulation is greater than with small fuel quantities, as particularly with small fuel quantities the temperature regulating device is in danger of working unsteadily.

In a governing device a distinction must be made between the "actual value" and the "desired value" of the engine operating condition to be regulated, for example, output, or the speed, or the pressure, or the temperature, which may be necessary or desirable to govern.

In the case of the marine plant chosen as example in Fig. 1, the "desired value" of the speed of the ship is ordered from the bridge, and the corresponding "desired value" of the output of the turbine is then set by the engine room watch by hand lever 34. This hand lever 34 does not vary the output of turbine 21 directly, but influences it indirectly, in that, instead of the direct influencing, it sets (by means of 71, 82, 76) at the speed governor 28 driven by the turbine 13 another "desired value" of the speed of turbine 13, i. e. corresponding to the "desired value" of the output of turbine 21. Consequently the governor 28 has a device for varying the "desired value" of the speed of turbine 13. The speed governor 28, adjusted to, for instance, a higher "desired value," then tends to suit the "actual value" of the speed of turbine 13 to the "desired value," i. e. to increase it. Also this speed governor in its turn works indirectly, in that it does not influence the turbine 13 directly, but instead of this the turbine 21, and in fact in the first moment in an apparently opposite sense. In order to obtain the sought increasing of the "actual value" of the output of turbine 21, it first of all reduces the energy fed to turbine 21, so that its output in the first moments does not increase, but diminishes. But this initial reduction in the energy fed to turbine 21 has the consequence that the pressures in the circuit begin to rise, and that therefore also the speed of turbine 13 and with it the speed of the compressors 1, 3 and 22 rise, with in consequence an additional and more rapid rise in the pressure and thereby an additional and more rapid rise in the "actual value" of the speed of turbine 13, until this "actual value" finally reaches its "desired value," and thereby also the "actual value" of the output of turbine 21 reaches its "desired value." During the whole of this operation, the fuel feed to burner 19 is at the

beginning only increased by an amount limited by the device 107-109; but, with rising pressure in the circuit, this device—by means of the device 110-112 influenced by the pressure in the circuit—gives an always increasing fuel feed corresponding to that pressure. In connection with this, the temperature is supervised by means of the thermostat 63 and associated apparatus.

In the marine plant chosen as example in Fig. 1, the turbine 21 has only an overspeed safety governor 40, but not a speed regulating governor, for in a marine plant there is a certain propeller speed corresponding to each output. On the other hand, in plants which are driving not a propeller but, for instance, an electric generator, the order to vary the "desired value" of the output of turbine 21 is given not from the bridge but from the load itself. The turbine 21 or the electric generator driven by it must then be provided with a device responsive to load, for example with a speed governor, or possibly with a device influenced by the electrical load, this varying the setting of the lever 34 automatically, instead of the engine room watch doing it. If, contrary to what has been said above, the output of the turbine 21 is to be diminished, the operations are the same but in the contrary sense, at any rate as long as the position of the lever 34 is varied only by a slight amount, or only slowly by a greater amount in the sense of reducing the "desired value" of the output. If on the other hand, the engine room watch finds it necessary to change the position of the lever 34 quickly by a very great amount in the sense of diminishing the "desired value," the lever 18 then pushes the control piston 91 up high, and thereby causes the same effect as if the safety governor 40 were to come into operation.

I claim:

1. In a gas turbine plant of the type including a compressed air circuit which includes a circuit compressor, a gas heater having a combustion chamber and a heat exchanger for heating gas by heat exchange without intermixture with combustion products from said chamber, a conduit connecting an outlet of said compressor to an inlet of said exchanger, a circuit turbine, a conduit connecting an outlet of said exchanger to an inlet of said circuit turbine, and a conduit connecting an outlet of said circuit turbine to an inlet of said compressor; an extraction branch which includes a conduit connecting an outlet of said compressor to an inlet of said chamber, an extraction turbine, and a conduit connecting an outlet of said chamber to an inlet of said extraction turbine; and a make-up branch which includes means for delivering air to said circuit in a quantity to replenish air passing from said circuit to said chamber; the combination which comprises a speed governor driven by said circuit turbine and a flow control device influenced by said governor controlling the flow of combustion products from said chamber to reduce said flow in response to a drop in speed of said circuit turbine.

2. A combination according to claim 1 in which the flow control device regulates the volume of combustion products entering the extraction turbine.

3. A combination according to claim 1 in which the flow control device regulates the in-flow cross-section of the extraction turbine.

4. A combination according to claim 1 in which the circuit turbine drives the compressor and the extraction turbine drives the plant load.

11

5. A combination according to claim 1 in which the extraction turbine is fitted with a by-pass around at least one stage and the flow control device regulates the flow through said by-pass.

6. A combination according to claim 1 in which a safety governor is driven by the extraction turbine, a cut-off valve in the conduit between the combustion chamber and said extraction turbine controlled by said safety governor, an outlet to atmosphere from said conduit between said chamber and said cut-off valve, an outlet valve regulating the flow through said outlet controlled by said safety governor, and an adjustable stop limiting the maximum opening to which said outlet valve can be set controlled by the circuit turbine governor.

7. In a gas turbine plant of the type including a compressed air circuit which includes a circuit compressor, a gas heater having a combustion chamber and a heat exchanger for heating gas by heat exchange without intermixture with combustion products from said chamber, a conduit connecting an outlet of said compressor to an inlet of said exchanger, a circuit turbine driving said circuit compressor, a conduit connecting an outlet of said exchanger to said inlet of said circuit turbine, and a conduit connecting an outlet of said circuit turbine to an inlet of said compressor; an extraction branch which includes a conduit connecting an outlet of said circuit compressor to an inlet of said chamber, an extraction turbine not mechanically connected to said circuit compressor, and a conduit connecting an outlet of said chamber to an inlet of said extraction turbine; and a make-up branch which includes a make-up compressor driven by said circuit turbine and a conduit connecting an outlet of said make-up compressor to a point in said circuit; the combination which comprises a speed governor driven by said circuit turbine, means for varying the speed of said circuit turbine, an isodrome device controlled by said speed governor and controlling said speed varying means, and means for setting the equilibrium value of said isodrome device to correspond to any desired circuit turbine speed.

8. A combination according to claim 7 in which the means for varying the speed of the circuit

12

turbine include means for regulating the flow from the combustion chamber.

9. A combination according to claim 8 in which the means for regulating the flow from the combustion chamber include means for controlling the quantity of combustion products supplied to the extraction turbine.

10. A combination according to claim 7 in which the means for varying the speed of the circuit turbine include a by-pass around at least a portion of the stages of at least one of the compressors and a flow control device influenced by a circuit turbine governor for controlling the flow through said by-pass.

11. A combination according to claim 7 in which the means for setting the equilibrium value of the isodrome device include means for adjusting the quantity of fuel supplied to the combustion chamber.

RENE STRUB.
